PREPARATION OF ORGANOALUMINUM COMPOUNDS IN THE PRESENCE OF A CATALYTIC AMOUNT OF Ti, Zr, Nb, V, Sc, U, OR Hf

Frederick J. Radd and Warren W. Woods, Ponca City, Okla., assignors to Continental Oil Company, Ponca City, Okla., a corporation of Delaware
No Drawing. Filed Sept. 26, 1960, Ser. No. 58,222
24 Claims. (Cl. 260—448)

The present invention relates, in general, to an improved process for preparing organoaluminum compounds. More particularly, the invention relates to the use of catalytic elements which provide improved reaction rates in the preparation of organoaluminum compounds. In a preferred embodiment, the invention relates to aluminum alloys containing catalytic elements, which aluminum alloys provide improved reaction rates in the preparation of dialkylaluminum hydrides. In another embodiment, the invention relates to the use of these aluminum alloys which contain catalytic elements in the preparation of dialkylaluminum hydrides.

The present invention is a continuation-in-part of application Serial No. 783,209, filed December 29, 1958, and now abandoned.

The preparation of dialkylaluminum hydrides can be illustrated by describing the preparation of diethylaluminum hydride. The conventional method for the preparation of diethylaluminum hydride involves the reaction of high-purity aluminum with triethylaluminum and hydrogen at an elevated temperature and pressure. This reaction is shown by the following equation:

Belgian Patent No. 546,432, issued March 24, 1956, to Karl Ziegler gives a description of this method. While this method has many advantages, it does have the disadvantage of having a relatively slow reaction rate.

The diethylaluminum hydride formed in the process of this invention can be reacted with ethylene to produce triethylaluminum as follows:

The over-all effect of the two reactions, then, is to produce three moles of triethylaluminum for each two moles of triethylaluminum initially present. The triethylaluminum gained from these processes can then be subjected to a "growth" reaction with additional olefin and the "growth" product in turn is converted into high-molecular-weight alcohols and α -olefins. These latter processes are well known to those skilled in the art.

While the preceding discussion has been concerned with diethylaluminum hydride and triethylaluminum, it may be well to note, again, that this has been solely for purposes of illustration. The present invention is not limited thereto. This will be apparent from a later discussion and the examples.

It is also known to prepare organoaluminum compounds (e.g., triethylaluminum) by the direct reaction of aluminum metal with hydrogen and an olefin. Such a process is disclosed by Horace E. Redman in U.S. Patent No. 2,787,626, issued April 2, 1957. Specifically, this patentee teaches a process for preparing triethylaluminum which comprises contacting comminuted aluminum (e.g., as aluminum shavings prepared under nitrogen) with sufficient triethylaluminum to wet the metal surface and then heating the reaction zone to a temperature between about 30° and 130° C. under 10 to 300 atmospheres' pressure of a gaseous mixture containing hydrogen and ethylene.

It is an object of the present invention to provide aluminum alloys which contain a reaction-promoting amount of one or more added catalytic metals.

2

It is still another object of the present invention to provide a process for preparing organoaluminum compounds wherein improved reaction rates are obtained in the process by using a reaction-promoting amount of one or more added catalytic metals.

It is yet another object of the present invention to provide a means for overcoming the harmful effects of certain elements when present in aluminum, and when said aluminum is used in the preparation of organoaluminum compounds, said means comprising the use of an aluminum alloy containing, in addition to the "harmful" elements, a reaction-promoting, and intentionally added, amount of one or more catalytic elements.

It is a preferred object of the present invention to provide an improved process for preparing dialkylaluminum hydrides wherein improved reaction rates are obtained in the process by the use of a reaction-promoting amount of one or more added catalytic metals.

It is another preferred object of the present invention to provide an improved process for preparing dialkylaluminum hydride, wherein improved reaction rates are obtained in the process by the use of an aluminum alloy containing a reaction-promoting, and intentionally added, amount of one or more catalytic metals.

Broadly stated, the present invention resides in our discovery that the use of a reaction-promoting amount of one or more catalytic elements in conjunction with aluminum gives improved reaction rates in processes wherein aluminum is used in the production of organoaluminum compounds.

We have discovered, also, that, in such processes, the use of aluminum alloys containing a reaction-promoting amount of one or more catalytic elements is more effective than the use of aluminum and the catalytic elements separately (i.e., not in alloyed form). We have also discovered that some elements do not increase the reactivity of aluminum when said aluminum (in alloy form) is used in the production of organoaluminum compounds. In addition, we have also discovered that some elements decrease the efficacy of the catalytic elements in the aluminum. By inference, then, we believe that these elements show a "retarding" or "negative" effect on the aluminum. We have discovered that by increasing the amount of the catalytic elements, the effect of these "negative" elements can be overcome.

Before proceeding to specific examples which illustrate our invention, it may be well to describe in general the materials of our invention and the terms used herein.

The term "organoaluminum compounds" as used herein refer to compounds having the general formula

wherein R_1 is a hydrocarbon radical, and R_2 and R_3 are hydrogen, halogen, or a hydrocarbon radical. The aforementioned hydrocarbon radical can contain from 2 to 40 carbon atoms and can be alkyl, aryl, alkaryl, or aralkyl.

Our invention is suitable for preparing organoaluminum compounds, such as the following:

- Diethylaluminum chloride
- Diethylaluminum bromide
- Diisobutylaluminum chloride
- Diisobutylaluminum bromide
- Diocetylaluminum chloride
- Dipentadecylaluminum bromide
- Didocosylaluminum chloride
- Diphenylaluminum hydride
- Diphenylaluminum chloride

- Di-para-tertiarybutylphenyl aluminum hydride
 Di-para-tertiarybutylphenyl aluminum chloride
 Diphenyloctylaluminum hydride
 Diphenyloctylaluminum chloride
 Triphenylaluminum
 Tri-para-tertiarybutylphenyl aluminum
 Triphenyloctylaluminum

Our invention is particularly suitable for preparing organoaluminum compounds, such as the following:

- Diethylaluminum hydride
 Diisobutylaluminum hydride
 Dioctylaluminum hydride
 Dipentadecylaluminum hydride
 Didocosylaluminum hydride
 Ditetracontylaluminum hydride
 Triethylaluminum
 Triisobutylaluminum
 Trioctylaluminum
 Tripentadecylaluminum
 Tridocosylaluminum

The elements which we have found to improve the efficacy of aluminum, in processes wherein aluminum is used to produce organoaluminum compounds, are the following: titanium, zirconium, niobium, vanadium, hafnium, scandium, and uranium. It is of interest that in general these elements conform to the following designation: (1) they are hydride formers; (2) most of the elements (at least titanium, zirconium, vanadium, and niobium) form peritectic binary systems with aluminum, and (3) they are apparently electronegative to aluminum even though scandium, uranium, and hafnium appear to be above aluminum in the usual chart. While most of the elements which work are peritectic-formers with aluminum, all of the elements which form peritectics with aluminum do not work. For example, barium, lanthanum, and cerium will form a peritectic with aluminum. Yet, they do not work in our invention. It should be noted that, while we have tested some fifty-one metallic elements in aluminum alloys, only the above-listed seven have been found to work.

Of the elements which work in our invention, the following are preferred: titanium, zirconium, niobium, vanadium, scandium, and uranium. Still further, of these, titanium and zirconium are the most preferred. In addition, it should be noted that combinations of the elements can be used.

We have found that the efficacy of the elements varies. For example, for a given level of reactivity in 99.99 percent aluminum, we have found that 200 parts per million (p.p.m.) of titanium is equalled, roughly, by 20 p.p.m. zirconium. In order to more concisely teach our invention, the following tables give the lower limits of efficacy for the catalytic elements of our invention.

Table I gives the lower limits of efficacy for the catalytic elements when incorporated in very pure (99.99 percent) aluminum. Table II gives the lower limits of efficacy for the catalytic elements when incorporated in aluminum of about 99.4 percent purity, which corresponds to commercially available aluminum.

TABLE I
Lower Effective Limits of Catalytic Elements in 99.99 Percent Aluminum

Element	Suitable, p.p.m.	Preferred, p.p.m.
Hafnium	about 1,000	about 5,000
Titanium	about 100	about 200
Zirconium	about 5	about 20
Niobium	about 1,000	about 5,000
Vanadium	about 1,000	about 2,500
Uranium	about 200	about 1,000
Scandium	about 200	about 2,000

TABLE II
Lower Effective Limits of Catalytic Elements in 99.4 Percent Aluminum

Element	Suitable, p.p.m.	Preferred, p.p.m.
Hafnium	about 2,000	about 10,000
Titanium	about 200	about 500
Zirconium	about 50	about 500
Niobium	about 5,000	about 10,000
Vanadium	about 5,000	about 10,000
Uranium	about 600	about 1,200
Scandium	about 400	about 1,000

In the preceding tables the term "suitable" refers to that lower limit which shows a perceptible optical or weight loss effect on the reaction involved. The term "preferred" refers to that lower limit wherein a practically important effect is noted.

While theoretically no upper limit exists for these catalytic elements, we believe that, from a practical viewpoint, it is not necessary, under most circumstances, to add more than 2 percent (by weight) of the catalytic element or elements to the aluminum. Usually, it will not be necessary to add more than 1 percent (by weight) of the catalytic element or elements to the aluminum.

In addition, it may be well to mention that each increase in the amount of catalytic element in the aluminum alloy to a certain level gives an improvement in reactivity. Stated another way, the higher the concentration of the catalytic element in the aluminum alloy, the greater the reactivity. However, for each element, there is a point of diminishing benefits or "leveling off." In other words, at this point the addition of more catalytic elements produces only a slight increase in reactivity. We believe that in plant practice it is desirable to use levels of catalytic elements at least equal to or greater than the "preferred" levels, but the plant levels will, for purposes or economy, be less than the 2 percent indicated as the maximum. For example, in plant practice it is desirable, when using titanium or zirconium, to use these elements in an amount of at least 0.02 percent, preferably 0.05 percent, by weight.

We have found that certain elements (e.g., iron, silicon, copper, tin, lead, and nickel) adversely affect the reactivity of the aluminum. The first three of this series occur as natural impurities in most commercially available aluminums. These elements are referred to as "negative" elements in the sense that they act to decrease the effectiveness of the catalytic elements. However, we have found that the increased addition of the catalytic elements overcomes the effect of the "negative" elements. Since some of these "negative" elements (e.g., iron and silicon) are found in some of the commercial grades of aluminum, our invention has considerable commercial significance. It is readily apparent that the addition of one or more of our catalytic elements can convert an "inactive" aluminum (i.e., an aluminum which is unreactive or very slow in processes for preparing organoaluminum compounds) to an "active" aluminum.

In addition, we have found that combinations of the catalytic elements can be used. In other words, the ternary and quaternary aluminum alloys containing the catalytic elements can be used.

The term "aluminum alloy" as used herein and in the appended claims refers to aluminum alloys wherein the catalytic elements have been deliberately added to the aluminum. The catalytic elements can be added to the aluminum by any of the means known to those skilled in the art. Examples of metallurgical means by which the catalytic elements can be added include the following (1) the elements can be added directly; (2) the elements, alloys, or inorganic salts can be added to the primary electrolysis cells; and (3) reductive compounds or mixtures of the elements can be added to the melting furnace. In addition, the term "aluminum alloy" as used herein

and in the appended claims refers to aluminum alloys containing at least 98 percent by weight of aluminum.

Another means by which the catalytic elements can be used is by blending aluminum alloys containing a higher-than-necessary concentration of the catalytic elements with aluminum or aluminum alloys containing none, or less than a reaction-promoting amount, of the catalytic elements. By this means, reaction-promoting amounts of the catalytic elements can be maintained in the reaction system.

While we do not wish to be bound by any particular theoretical hypothesis as to how these alloying metals accelerate the reaction, our present belief is that the effect is catalytic and positive in nature. The term "catalytic" elements has been used herein in order to have a generic term for the elements which work effectively for reaction acceleration in the aluminum alloys used in preparing organoaluminum compounds. From the evidence we have obtained, it appears that the observed catalytic effect is not due to reduction in grain size, which coincidentally occurs in most of the catalytic aluminum alloys used.

It may be well to explain that when we refer herein to improvements in the reaction rate, in processes for preparing organoaluminum compounds, we mean for the term to include associated decreases in induction time. It is readily apparent that both serve to decrease the overall reaction time, which is the primary practical concern.

The shape or form of the aluminum alloy used in preparing organoaluminum compounds does not fall within the scope of our invention. Generally, workers in this field have used comminuted aluminum (e.g., atomized particles or machined shavings) because a large surface area per unit of weight is afforded. In addition, it is often customary to treat the aluminum to remove any coating of aluminum oxide. Ball milling of aluminum powder in a kerosene-triethylaluminum solution is an example of the latter procedure. Regardless of the form or previous treatment of the aluminum, the addition of the catalytic elements improves the reactivity of the aluminum.

The term "reaction-promoting" amount as used herein refers to that amount which catalyzes the reaction. The term is synonymous with "catalytic amount"; however, in view of the term "catalytic" element, the alternative term has been used.

Generally, the reaction of the trialkylaluminum and hydrogen with the aluminum alloy is conducted at a temperature of 80 to 200° C., more preferably 100 to 150° C., and at a pressure of 60 to 350 atmospheres. An excess of hydrogen is used. The reaction will occur at any mole ratio of aluminum to trialkylaluminum of from 0.1 to 1, to 10 to 1. More preferably, the mole ratio of aluminum to triethylaluminum is from 1 to 1, to 4 to 1.

The aluminum alloys of our invention can also be used in the process of Redman (U.S. Patent No. 2,787,626), discussed previously herein. Use of our aluminum alloys containing one or more catalytic elements provides for an increased reaction rate in said process.

In order to disclose more clearly the nature of the present invention and the advantages thereof, reference will hereinafter be made to certain specific embodiments which illustrate the flexibility of the herein-described process. It should be clearly understood, however, that this is done solely by way of example and is not to be construed as a limitation upon the spirit and scope of the appended claims.

EXAMPLE I

Aluminum having a purity of 99.99+ percent was used in this example. One batch of this aluminum was cast into $\frac{3}{8}$ -inch diameter rods. A second batch containing 99.85 percent of the same high-purity aluminum and 0.15 percent of pure titanium metal was cast into $\frac{3}{8}$ -inch diameter rods.

EXAMPLE II

Thirty grams (1.1 moles) of the aluminum rod containing 0.15 percent titanium of Example I was cut into

fine shavings into a dilute solution of triethylaluminum in xylene. The solution containing 228 grams (2.00 moles) of triethylaluminum with the aluminum shavings was charged to a 1-liter pressure bomb. The bomb was sealed and heated with stirring to 120° C. It was then pressured to 4000 p.s.i.g. using hydrogen. These conditions were maintained for 1 hour. At the end of this time, the pressure was released, the bomb cooled, and the product isolated. Sixteen grams of unreacted aluminum was recovered. The yield of diethylaluminum hydride was 52 percent of theoretical based on the aluminum consumed.

EXAMPLE III

The procedure of Example II was followed with the exception that 28 grams (1.04 moles) of the pure aluminum rod of Example I was used. Approximately 26 grams of unreacted aluminum was recovered at the end of the procedure. The yield of diethylaluminum hydride was 7 percent of theoretical based on the aluminum consumed.

EXAMPLE IV

In order to more rapidly evaluate the efficacy of various aluminum alloys, a "screening test" was used. The equipment consisted of a standard, one liter, stirred (640 r.p.m.) autoclave. A stainless steel sample holder was mounted upon the stirrer shaft so as to hold eight cylindrical test specimens of $\frac{3}{8}$ -inch diameter by 1-in. length. In conducting a run, one end of each of these cylinders was metallographically polished to afford a sensitive means to study the surface topography after the triethylaluminum-hydrogen solution attacks. The polished cylinders were placed on the sample holder, 500 milliliters of triethylaluminum was added to the autoclave, and the autoclave was pressured with hydrogen to 2000 p.s.i.g. and 250° F. The run was conducted for three hours. A standard coupon of alloy of 1000 p.p.m. titanium in 99.99 percent aluminum was used as a reference in each run. Each coupon was weighed before and after the run.

The alloys tested were prepared by air melting in a pure graphite crucible heated by an electric resistance furnace. A weighed amount of the alloying element was added to a weighed amount of aluminum of 99.99 percent purity.

A loss in weight of the coupon indicated that the particular alloy in the coupon was reactive.

Several runs were made using 99.99 percent aluminum coupons. Due to the limited surface area of the aluminum coupons, due to the fact that these were not mechanically or chemically activated, and due to the particular reaction conditions, no weight loss was noted for these coupons.

Using this procedure, many aluminum alloys were "screened." The results for the ones which showed a weight loss, thereby indicating a catalytic element present, are shown in Table III.

TABLE III
Aluminum Alloy Reactivity; 99.99 Percent Aluminum Containing—

Element	Amount Added, p.p.m.	Weight Loss (Gram)
Titanium	20	0.0002
Do	80	0.0004

8
EXAMPLE IX

Charge:

150 grams triisobutylaluminum
27.3 grams aluminum powder (99.99% pure)

5 Procedure: The triisobutylaluminum and aluminum powder (which were in a molar ratio of 3 to 4) were charged to a 1-liter, stirred autoclave. The autoclave was heated to 250° F. and pressured to 2,000 p.s.i.g. with hydrogen. Reaction was conducted for 1 hour. The reaction was then stopped and the products were centrifuged to remove suspended aluminum.

10 Results: An aluminum analysis of the product indicated that none of the triisobutylaluminum had been converted to diisobutylaluminum hydride.

EXAMPLE X

Charge:

150 grams triisobutylaluminum

20 27.3 grams aluminum alloy powder (99.99% aluminum containing 2,000 p.p.m. zirconium)

Procedure: The procedure was exactly the same as used in Example IX.

25 Results: An aluminum analysis of the product indicated that 35.2 percent of the triisobutylaluminum was converted to diisobutylaluminum hydride.

EXAMPLE XI

Charge:

30 150 grams trioctylaluminum

14.8 grams aluminum powder (99.99% pure)

Procedure: The procedure was the same as in Example IX.

35 Results: An aluminum analysis of the product indicated that 3.1 percent of the trioctylaluminum had been converted to dioctylaluminum hydride.

EXAMPLE XII

Charge:

40 150 grams trioctylaluminum

14.8 grams aluminum alloy powder (99.99% aluminum containing 2,000 p.p.m. zirconium)

45 Procedure: The procedure was the same as in Example IX.

Results: An aluminum analysis of the product indicated that 18.8 percent of the trioctylaluminum had been converted to dioctylaluminum hydride.

EXAMPLE XIII

Charge:

50 150 grams "growth product" ¹ (sample No. RGR-3-178)
12 grams aluminum powder (99.99% pure)

55 Procedure: The procedure was the same as in Example IX.

Results: An aluminum analysis of the product indicated that 9.2 percent of the "growth product" had been converted to the dialkylaluminum hydride.

60 ¹ The term "growth product" refers to a mixture of alkyl-aluminum compound made by repeated addition of ethylene to trialkylaluminum. A typical sample of "growth product" has the following analysis (alkyl groups):

Carbon content of alkyl group :	Wt. percent
C ₂	0.59
C ₄	3.52
C ₆	10.57
C ₈	17.17
C ₁₀	20.33
C ₁₂	18.30
C ₁₄	13.44
C ₁₆	8.27
C ₁₈	4.40
C ₂₀	2.06
C ₂₂	0.85
C ₂₄	0.32
C ₂₆	0.10
C ₂₈	0.04
C ₃₀	0.01

9 EXAMPLE XIV

Charge:

150 grams "growth product" (same as used in Example XII)

12 grams aluminum alloy powder (99.99% aluminum containing 2,000 p.p.m. zirconium)

Procedure: The procedure was exactly the same as used in Example IX.

Results: An aluminum analysis of the product indicated that 27.2 percent of the "growth product" had been converted to the dialkylaluminum hydride.

EXAMPLE XV

In this example, three samples of aluminum powder were atomized by the Aluminum Company of America. Two of the samples were prepared from 99.99 percent pure aluminum. The third sample was prepared from 99.99 percent purity molten aluminum to which had been added 0.078 percent of titanium.

Each of the samples was ball-milled for six hours in a kerosene-triethylaluminum solution. A certain amount, 108 grams or 4 moles, of the ball-milled aluminum was then charged to a 1-liter autoclave with 342 grams (3 moles) of triethylaluminum. The autoclave was heated to 120° C. and then pressured to 2,000 p.s.i.g. with hydrogen. These conditions were maintained, depending upon the reactivity of the sample, from 30 minutes to as long as four hours.

The results of these tests are shown in Table VIII. The data therein show the percentages of triethylaluminum converted to diethylaluminum hydride for $\frac{1}{2}$ hour, 2 hours, and 4 hours. In addition, the chemical analysis of each powder is shown in Table VIII.

TABLE VIII

Reactivity Measurements; Aluminum Powders With and Without Catalytic Elements

Reynolds 120 #7150 ¹	0.010	0.22		LNV-893-123	1.16

¹ Commercial powder; no titanium added.

EXAMPLE XVI

In this example, three samples of aluminum powder containing varying amounts of titanium were prepared under commercial aluminum powder production (spray-

10

ing liquid aluminum) conditions by Reynolds Metals Company. The aluminum powder corresponded to "Reynolds 120" commercial powder, with the exception of the added titanium. For purposes of comparison, five samples of "Reynolds 120" commercial (99.3+ percent purity) aluminum powders were tested for reactivity. These powders had no titanium added; whatever titanium present occurred naturally. The powder contained small amounts of iron and silicon.

10 These eight samples of aluminum powder were ball-milled and were tested for reactivity in the manner described in Example XIV. The results are shown in Table IX. The data therein show the time in hours required to obtain an 80 percent conversion of triethylaluminum to diethylaluminum hydride.

15 From the data in Tables VI and VII the "activity decreases" of the catalytic elements, due to the presence of impurity or "negative" elements, can be estimated. Using 1000 p.p.m. concentration of titanium and zirconium in 20 the aluminum alloy as the reference point, the results are as shown below.

Element and Concentration	Ti 1,000 p.p.m., percent	Zr 1,000 p.p.m., percent
Fe (1 p.p.m.)	-0.023 (decrease)	-0.009
Si (1 p.p.m.)	-0.032	-0.026

Mn (1 p.p.m.)	-0.022	-0.014

25 While particular embodiments of the invention have been described, it will be understood, of course, that the invention is not limited thereto, since many modifications may be made; and it is, therefore, contemplated to cover by the appended claims any such modifications as fall within the true spirit and scope of the invention.

30 The invention having thus been described, what is claimed and desired to be secured by Letters Patent is:

35 1. In a process for preparing organoaluminum compounds, said compounds being characterized as having the general formula

40 45 wherein R_1 and R_2 are hydrocarbon radicals containing from 2 to 40 carbon atoms and R_3 is selected from the group consisting of hydrogen and a hydrocarbon radical containing from 2 to 40 carbon atoms, by the reaction of at least one organic compound and aluminum, the improvement comprising carrying out the process in the presence of an added reaction-promoting amount of at least about 5 parts per million of at least one catalytic element selected from the group consisting of titanium, zirconium, niobium, vanadium, scandium, uranium, and hafnium.

50 55 2. In a process for preparing organoaluminum compounds, said compounds being characterized as having the general formula

60 65 70 wherein R_1 and R_2 are hydrocarbon radicals containing from 2 to 40 carbon atoms and R_3 is selected from the group consisting of hydrogen and a hydrocarbon radical containing from 2 to 40 carbon atoms, by the reaction of at least one organic compound and aluminum, the improvement comprising carrying out the process with an aluminum alloy containing at least 98 weight percent of aluminum and a reaction-promoting amount, at least about 5 parts per million, of at least one added catalytic element selected from the group consisting of titanium,

zirconium, niobium, vanadium, scandium, uranium, and hafnium.

3. In a process for preparing dialkylaluminum hydride by the reaction of a trialkylaluminum, the alkyl radicals of said trialkylaluminum containing from 2 to 40 carbon atoms, with hydrogen and aluminum at an elevated temperature and superatmospheric pressure, the improvement comprising carrying out the reaction with an aluminum alloy containing at least 98 weight percent aluminum and a reaction-promoting amount, at least about 5 parts per million, of at least one added catalytic element selected from the group consisting of titanium, zirconium, niobium, vanadium, scandium, uranium, and hafnium.

4. The process for the preparation of diethylaluminum hydride comprising reacting triethylaluminum with hydrogen and an aluminum alloy at an elevated temperature and superatmospheric pressure, wherein said aluminum alloy comprises about 98 to about 99.98 percent by weight of aluminum and a reaction-promoting amount in the range of about 0.02 to about 2 percent by weight of at least one added catalytic element selected from the group consisting of titanium, zirconium, niobium, vanadium, scandium, uranium, and hafnium.

5. The process, as defined in claim 2, wherein the catalytic element is titanium.

6. The process, as defined in claim 2, wherein the catalytic element is zirconium.

7. The process, as defined in claim 2, wherein the catalytic element is niobium.

8. The process, as defined in claim 2, wherein the catalytic element is vanadium.

9. The process, as defined in claim 2, wherein the catalytic element is scandium.

10. The process, as defined in claim 2, wherein the catalytic element is uranium.

11. The process, as defined in claim 2, wherein the catalytic element is hafnium.

12. A process for the preparation of diethylaluminum hydride comprising reacting triethylaluminum with hydrogen and an aluminum alloy at an elevated temperature and superatmospheric pressure, wherein said aluminum alloy comprises about 99 to about 99.95 percent by weight of aluminum and a reaction-promoting amount in the range of about .05 to about 1 percent by weight of at least one added catalytic element selected from the group consisting of titanium, zirconium, niobium, vanadium, scandium, uranium, and hafnium.

13. The process, as defined in claim 12, wherein the catalytic element is titanium.

14. The process, as defined in claim 12, wherein the catalytic element is zirconium.

15. The process, as defined in claim 12, wherein the catalytic element is niobium.

16. The process, as defined in claim 12, wherein the catalytic element is vanadium.

17. The process, as defined in claim 12, wherein the catalytic element is scandium.

18. The process, as defined in claim 12, wherein the catalytic element is uranium.

19. The process, as defined in claim 12, wherein the catalytic element is hafnium.

20. In a process for preparing trialkylaluminum, the

alkyl radical of said trialkylaluminum containing from 2 to 40 carbon atoms, by the reaction of aluminum with hydrogen and an olefin at an elevated temperature and superatmospheric pressure, the improvement comprising carrying out the reaction with an aluminum alloy containing at least 98 weight percent aluminum and a reaction-promoting amount in the range of at least about 5 parts per million of at least one added catalytic element selected from the group consisting of titanium, zirconium, niobium, vanadium, scandium, uranium, and hafnium.

21. In a process for preparing triethylaluminum by the reaction of aluminum with hydrogen and ethylene at an elevated temperature and superatmospheric pressure, the improvement comprising carrying out the reaction with an aluminum alloy wherein said aluminum alloy comprises about 98.0 to about 99.98 percent by weight of aluminum and a reaction-promoting amount in the range of about 0.02 to about 2.0 percent by weight of at least one added catalytic element selected from the group consisting of titanium, zirconium, niobium, vanadium, scandium, uranium, and hafnium.

22. In a process for preparing triethylaluminum by the reaction of aluminum with hydrogen and ethylene at an elevated temperature and superatmospheric pressure, the improvement comprising carrying out the reaction with an aluminum alloy wherein said aluminum alloy comprises about 99.0 to about 99.95 percent by weight of aluminum and a reaction-promoting amount in the range of about 0.05 to about 1.0 percent by weight of at least one added catalytic element selected from the group consisting of titanium, zirconium, niobium, vanadium, scandium, uranium, and hafnium.

23. In a process for preparing dialkylaluminum hydride, the alkyl radicals of said dialkylaluminum hydride containing from 2 to 40 carbon atoms, by the reaction of a trialkylaluminum with hydrogen and aluminum at an elevated temperature and superatmospheric pressure, the improvement comprising carrying out the process in the presence of a reaction-promoting amount of at least about 5 parts per million of at least one added catalytic element selected from the group consisting of titanium, zirconium, niobium, vanadium, scandium, uranium, and hafnium.

24. In a process for preparing diethylaluminum hydride by the reaction of triethylaluminum with hydrogen and aluminum at an elevated temperature and superatmospheric pressure, the improvement comprising carrying out the process in the presence of a reaction-promoting amount of at least about 5 parts per million of at least one added catalytic element selected from the group consisting of titanium, zirconium, niobium, vanadium, scandium, uranium, and hafnium.
